UNITED STATES PATENT OFFICE.

HENRY S. RAUCH, OF JACKSON, MICHIGAN.

STARTING DEVICE FOR EXPLOSIVE-ENGINES.

1,089,962.

Specification of Letters Patent.

Patented Mar. 10, 1914.

Application filed February 2, 1912. Serial No. 674,909.

To all whom it may concern:

Be it known that I, HENRY S. RAUCH, a citizen of the United States, residing at Jackson, in the county of Jackson and State 5 of Michigan, have invented certain new and useful Improvements in Starting Devices for Explosive-Engines, of which the following is a specification.

This invention relates to starting devices 10 for explosive engines, and it has for one of its objects the provision of a mechanism which is hand-operable and adapted to rotate the engine shaft several times for each straight-line movement of the operating 15 lever.

The invention has, furthermore, for its object the provision of novel means for automatically connecting and disconnecting the hand-operated shaft of the device with 20 and from the engine-shaft, all as will hereinafter appear and be particularly defined in the claims.

The invention has been clearly illustrated in the accompanying drawings, in which 25 similar characters denote similar parts, and in which—

Figure 1 is a top view of my improved device, Fig. 2 is an end view thereof, Fig. 3 shows a central longitudinal section of 30 the same, Fig. 4 is a view corresponding to Fig. 1, and illustrates an intermediate position of some of the parts during their operation, Fig. 5 is a section on line 5, of Fig. 1, on an enlarged scale, and Fig. 6 represents 35 the element shown in Fig. 5 in another position.

Briefly stated the present device is intended to replace the crank commonly used when starting an explosive engine of the 40 compression type, especially in automobiles, power boats, and the like, so that a hand lever may be used with a single stroke in one direction to turn the engine-shaft over a number of times and thus start the engine 45 under its own power, whereupon the hand lever may be allowed to return and to automatically disengage the operating member of the device from the engine shaft.

Referring to the drawings, 10 denotes a 50 base plate provided with ways 11 for slidably supporting a reciprocatory slide 12. This slide has bearings 13, 14 in which is journaled a shaft 15 which constitutes the driving member for the engine shaft 16 to 55 which it may be coupled by a clutch member 17 coöperative with a similar member 18

on the engine shaft 16. The driver 15 carries a bevel pinion 19 fast thereon in constant engagement with a sector 20 journaled on a stud 21 securely held in the slide 12. 60 An extension 22 on the sector may be employed to connect the latter by a rod 23 with the hand-lever (not shown), for actuating the device. A torsional spring 24 surrounds the shaft 15 and has one end attached to the pinion 19, as at 24', while its other end 24'' rests against the upper face of the slide, the organization being such that said spring will return the shaft and sector rotatively to the position shown in 70 Fig. 1, in which the device is shown normal, and the retrograde movement of the sector limited by a stop-pin 25 striking against a holding-plate 26 whereby proper mesh is maintained between the sector and pinion, 75 as will be readily understood.

From the foregoing it will be seen that, a pull exerted on the rod 23 in the direction of arrow *a*, Fig. 1, the shaft 15 will be rotated, and, in order to bring the clutch 80 members 17, 18 into engagement so that the rotation of the shaft 15 may be utilized to operate the engine-shaft simultaneously, the entire slide 12 together with all the parts carried thereby, is positively moved toward 85 the left in Fig. 1, the result being accomplished by a roller 27 rotatable on a stud 28 held in the base 10, (see also Fig. 5), and engaging a cam 29 on the sector during its initial rotative movement. This means, 90 that the slide 12 will be moved bodily, with the sector, pinion, shaft, and clutch member 17 until the latter has fully engaged the clutch member 18, (see Fig. 4) whereupon the engine shaft will be carried along rotatively, and the torsional spring 24 placed under additional tension. When now the engine starts under its own power, and naturally at a greatly accelerated speed, the cam faces of the clutch-members will merely 95 push the slide back; the same thing will also occur when the pull on the rod 23 is released, in which case a spring 30 will tend to pull the slide and all its parts back to normal position, excepting that the roller 100 27 may come to rest against the inner face 31 of the sector-rim. Means are, therefore, provided for permitting the full return movement, rotatively, of the sector without necessarily moving the slide forward again. 105 In the present instance I accomplish this result by cutting the underside 25' of the

cam 29 on an incline, and the stud 28 together with its roller 27 are mounted for vertical or disappearing movement in base-plate 10, as against a spring 32 (see Fig. 6) which will allow the roller and stud to be depressed during the return movement of the sector, as indicated by arrow *b*.

As it may happen that the forward movement of the slide 12 may bring the adjacent faces of the clutch members into abutting relation, it may be desirable to render the engine-shaft member 18 slightly yieldable, as for instance by a spring 33 interposed between said member and a collar 34 fixed on the shaft 16.

Many changes may be made in the particular construction and organization of some of the component elements of my improved device without departing from the spirit of the invention.

I claim:

1. The combination with an engine shaft, and a clutch member thereon, of a driving shaft, a clutch member thereon, a slide on which said driving shaft is journaled, a stationary support for said slide, and a manually operable element carried by said slide and co-operating with said driving shaft and its support to shift said slide and driving shaft toward the engine shaft and simultaneously revolve said driving shaft.

2. The combination with an engine shaft, and a clutch member thereon, of a driving shaft, a clutch member thereon, a slide on which said driving shaft is journaled, a stationary support for said slide, and a sector carried by said slide and co-operating with said driving shaft and its support to shift the said slide and driving shaft toward the engine shaft and simultaneously revolve said driving shaft.

3. The combination with an engine shaft, and a clutch member thereon, of a driving shaft, a clutch member thereon, a slide for supporting said driving shaft, a sector journaled on said slide for rotating said driving shaft, and means controlled by the movement of said sector for moving said slide to bring said clutch members into engagement.

4. The combination with a frame, and an engine shaft, and a clutch member thereon, of a driving shaft, a clutch member thereon, a slide for supporting said driving shaft, a sector journaled on said slide for rotating said driving shaft, an abutment on the frame, and a cam controlled by the movement of

said sector and engaging said abutment for moving said slide to bring said clutch members into engagement.

5. The combination with an engine shaft, of a stationary base plate, a slide movable thereon, a shaft journaled on said slide, a sector pivoted on said slide and adapted to rotate said shaft, and means controlled by the movement of said sector for advancing said slide and shaft toward the engine shaft.

6. The combination with an engine shaft, of a stationary base plate, a slide movable thereon, a shaft journaled on said slide, a sector pivoted on said slide and adapted to rotate said shaft, an abutment on the plate, and a cam on said sector and engaging said abutment for advancing said slide and shaft toward the engine shaft.

7. The combination with an engine shaft, of a stationary base plate, an abutment on said base plate, a slide movable thereon, a shaft journaled on said slide, a sector pivoted on said slide and adapted to rotate said shaft, and a cam on said sector adapted to engage said abutment for advancing said slide and shaft toward the engine shaft, and means for returning said slide to normal position.

8. The combination with an engine shaft, of a stationary base plate, an abutment on said base plate, a slide movable thereon, a shaft journaled on said slide, a sector pivoted on said slide and adapted to rotate said shaft, and a cam on said sector adapted to engage said abutment for advancing said slide and shaft toward the engine shaft, and a spring for returning said slide to normal position.

9. The combination with an engine shaft, of a stationary base plate, an abutment on said base plate, a slide movable thereon, a shaft journaled on said slide, a sector pivoted on said slide and adapted to rotate said shaft, and a cam on said sector adapted to engage said abutment for advancing said slide and shaft toward the engine shaft, and means for returning said slide to normal position, said abutment being non-operative during the return movement of said sector.

In testimony whereof I affix my signature in presence of two witnesses.

HENRY S. RAUCH.
